UNITED STATES PATENT OFFICE

2,456,689

FLUID-PRESSURE MOTOR

Fred C. Eastman, Marblehead, Mass., assignor to
United Shoe Machinery Corporation, Flemington, N. J., a corporation of New Jersey

Original application August 28, 1942, Serial No. 456,564, now Patent No. 2,436,424, dated February 24, 1948. Divided and this application November 4, 1944, Serial No. 561,917

11 Claims. (Cl. 121—38)

1

This invention relates to fluid-pressure-operated mechanisms, and more particularly to a fluid-pressure-operated motor having means for causing automatic operation of the motor through a predetermined cycle. The invention is illustrated as embodied in a machine for setting fuses of shells. It should be understood, however, that in its broader aspects the invention is not so limited but is applicable to machines for operating on other types of work pieces. This application is a division of application for Letters Patent of the United States, Serial No. 456,564, filed August 28, 1942, in my name, now Patent No. 2,436,424.

An object of the invention is to provide an improved fluid-pressure-operated motor having a pressure-responsive mechanism arranged to cause the motor to operate in accordance with a predetermined cycle. To this end and in accordance with a feature of the invention, the motor includes a movable element movable in one direction or another in response to the admission of pressure fluid to one side or the other of said element, the element being connected to a work-engaging member, there being means for directing the fluid under pressure to one side of the element to move the work-engaging member into engagement with a work piece under heavy pressure and pressure-responsive means for directing the fluid under pressure to the other side of the element while the first side is still under pressure, thereby to reduce the pressure exerted by the work-engaging member on the work piece. As illustrated herein, the motor comprises a pair of pistons movable in cylinders, the flow of fluid into which is controlled by a pressure-responsive valve. In one position of the valve fluid is admitted behind the pistons, in a second position both behind and ahead of the pistons and in a third position it is admitted ahead of the pistons and exhausted from behind the pistons. This valve is movable step by step into its various positions in response to progressive increases in the pressure of the operating fluid. In accordance with a further feature of the invention this valve is controlled by a latch which cooperates with a member movable with the valve, the latch being arranged to hold the valve in one of several different positions thereby to permit step-by-step movement of the valve in response to increases in the pressure of the operating fluid.

The above and other features of the invention, including novel details of construction and combinations of parts, will now be more particularly

2

described by reference to the accompanying drawings and pointed out in the claims.

In the drawings,

Fig. 1 is a view in side elevation of a machine in which the invention is embodied;

Fig. 2 is a plan view of a portion of the machine shown in Fig. 1;

Fig. 3 is a bottom plan view of the portion of the machine shown in Fig. 2;

Fig. 4 is a vertical longitudinal section through the machine on a larger scale than Figs. 1 to 3;

Fig. 5 is a schematic view, partly in section, of the portion of the machine shown in Fig. 2;

Figs. 6, 7 and 8 are sectional views through the main control valve of the machine, showing the valve in different positions;

Figs. 9 and 10 are sectional views through another valve, showing it in two different positions; and

Fig. 11 is a vertical section through the work-engaging portion of the machine, illustrating a shell in operative relation thereto.

The invention is herein illustrated as embodied in a fuse setter 10 (Fig. 1) suitably mounted on the breech end of a gun 12. The shells to

be supplied to the gun may be carried by a suitable magazine 14 from which they are transferred

successively into fuse-setting position and then into ramming position by a transfer tray 16. This

tray is secured by a depending arm 18 to a pair of links 20 and 22. The link 22 is journaled

on a lateral extension of a trunnion 24 by which the gun is supported and the link 20 is connected

by a link 26 to the trunnion. A duplicate set of

links (not shown) may be provided at the opposite side of the gun better to support the tray.

A rod 28 connected to the link 22 serves to raise

and lower the link, thereby to move the transfer tray vertically. The rod 28 may be manually op-

erated or may be power operated by suitable mechanism (not shown). The tray is movable

upwardly from the position illustrated to receive

a shell from the magazine 14, after which it is

lowered to carry the shell into position to have

its fuse set by the mechanism 10. At the conclu-

sion of the fuse-setting operation, the tray is

lowered still further to carry the shell into align-

ment with the breech of the gun, whereupon a

rammer 30 forces the shell into the breech.

The fuse-setting mechanism 10 comprises a

plurality of knives 32 (one of which is shown

in Fig. 4) which are preferably three in number

and are arranged to engage the fuse ring F of a

shell S at points spaced approximately 120° apart.

Each knife 32 is formed at the end of a lever 34

pivoted at 36 between spaced ears 38 projecting outwardly from a rotatable support 40. Surrounding the inner ends of the levers in a spring 42 urging the levers in a direction to move the knives 32 outwardly of the support. A plunger 44 is normally maintained in the position shown in Fig. 4 to hold the inner ends of the levers 34 separated against the force of the spring 42, thereby maintaining the knives 32 in operative positions. The support 40 is rotatable within a housing 46 so that it may be turned relatively to the housing after the knives are in engagement with the fuse ring F, thereby to turn the fuse ring and set the fuse. For holding the shell against turning movement at this time a plurality of pins 48, preferably three in number, are slideable within bosses 50 formed in the forward end of the housing 46 and are movable toward the shell to grip it rearwardly of the fuse ring, as illustrated in Fig. 11. Bellcrank levers 52 pivoted between ears 54 on the housing 46 engage the outer ends of the pins for moving them inwardly into engagement with the shell. These levers are connected by links 56 to pistons 58 slideable in cylinders 60 formed in the housing 46 so that upon the introduction of fluid under pressure in the cylinders behind the pistons the pins are moved into gripping relationship with the shell. The pins 48 are provided with heads 61 which prevent the pins from dropping from the bosses 50 when no shell is being operated upon.

The housing 46 is movable lengthwise of the shell positioned in front of it to carry the knives 32 into engagement with the fuse ring, as shown in Fig. 11. For this purpose the housing is secured by arms 62, 63 (Figs. 2 and 3) to rods 64, 66 movable lengthwise of the gun. The forward ends of the rods are supported for sliding movement in a frame member 68 which is in turn secured to bars 70 carried by the breech end of the gun. The rearward ends of the rods 64, 66 are formed as pistons 72, 74 (Fig. 5) slideable in cylinders 76, 78. These cylinders are formed in a frame member 80 which is also secured to the bars 70. Upon the introduction of fluid under pressure in the cylinders 76, 78 behind the pistons 72, 74, the rods 64, 66 carrying the arms 62, 63 are moved in a direction to carry the housing 46 and the support 40 for the knives toward the shell S until the knives are forced into engagement with the fuse ring F, as shown in Fig. 11. The pins 48 are then moved into engagement with the shell back of the fuse ring, as will be described, to hold the shell against rotative movement after which the support 40, and with it the knives 32, is rotated a predetermined amount to set the fuse. After the fuse has been properly set, the turning movement of the support 40 is interrupted and the plunger 44 is retracted to permit the knives 32 to be moved by the spring 42 outwardly of the support 40 and out of engagement with the fuse ring. The levers 52, acting on the pins 48 are then operated to release the force exerted by the pins 48 on the shell, after which the housing 46 is moved back to its initial position so that the shell with the fuse properly set may be moved by the tray 16 into ramming position.

The cycle of operations is controlled, at least partly, by a main control valve mechanism 82 (Figs. 5 to 8) associated with the cylinder 76. This control mechanism comprises a slide valve member 84 which includes a pair of valve elements 86 and 88 slideable within a valve chamber 90. Fluid under pressure is admitted by a sup-

ply pipe 92 into the valve chamber between the valve elements 86 and 88. Fluid exhausts from the valve chamber through an exhaust port 94, a spring-pressed check valve 96 which prevents escape of fluid from the valve chamber until the pressure has reached a predetermined amount, and thence to a fluid reservoir (not shown) by way of a pipe 97. The rearward end of the valve member 84 is formed as a piston 98 which is subjected, during the operation of the machine, to pressure on its rearward side to cause the valve to move to the left from the position shown in Fig. 6 in a step-by-step manner. Passageways 99 and 100 formed in the wall 101 between the valve chamber and the cylinder 76 provide communication between the valve chamber and opposite ends of the cylinder. The valve member 84 is formed with a passageway 102 providing communication between the outer sides of the valve elements 86 and 88. The valve member 84 includes a valve stem 104 which extends through the forward wall of the valve chamber and to the outer end of which is secured a finger 106 having a surface arranged to slide in contact with an adjacent surface of the cylinder 76. For restraining movement of the valve member from the position shown in Fig. 6 under the influence of pressure exerted on the rearward surface of the piston 98, a latch 108 is provided. This latch is pivoted at 110 between ears 111 on the exterior wall of the valve housing and is urged by a spring 112 toward the finger 106. Notches 114 and 116 are formed in the latch to receive sequentially the upper end of the finger 106. The latch thus holds the valve member in the position shown in Fig. 6 until the pressure exerted behind the piston 98 is sufficient to move the latch upwardly against the force of the spring 112, whereupon the valve member will move to the left until the finger 106 seats within the notch 116, as shown in Fig. 7. The valve member will remain in this position until the pressure on the piston 98 increases to a value which is sufficient to move the latch further upwardly against the increased resistance of the spring 112, whereupon the valve member will move to the position shown in Fig. 8.

With the valve member 84 in the position shown in Fig. 5, both the passageways 99 and 100 are closed by the valve elements 86 and 88 respectively and the machine is at rest. Provision is made for moving the valve member from the position of Fig. 5 into the position shown in Fig. 6. For this purpose a rod 120 located in front of the finger 106 on the valve stem 104 is supported for lengthwise movement in bosses 122, 124 (Fig. 2) projecting upwardly from the cylinder 76 and the frame member 68 respectively. Pivoted to the upper surface of the frame member 68 is a lever 126 having an end engageable with the adjacent end of the rod 120. The other end of this lever is connected by a link 128 (Fig. 4) to a lever 130 pivoted at 132 on the frame member 68. The lower end of the lever 130 is bent at 134 to be engaged by the nose of a shell as it is moved downwardly by the transfer tray 16 into the fuse-setting position. As this shell is thus moved downwardly, the lever 130 is moved in a counterclockwise direction, as viewed in Fig. 4, and acts through the link 128 and the lever 126 to move the rod 120 in the direction to move the valve member from the position of Fig. 5 to the position shown in Fig. 6. The valve member is maintained in the position shown in Fig. 5 when the machine is at rest by the latch 108,

which acts on the finger to maintain it in engagement with a screw 136, carried by an extension 138 of one of the arms 63.

Upon movement of the valve member to the position shown in Fig. 6 in response to movement of a shell into fuse-setting position, the passageways 99 and 100 are uncovered and fluid under pressure flows through the passageway 100 into the cylinder 76 behind the piston 72. Pipes 140 and 142 connect the cylinders 76 and 78 together at their two ends so that the fluid under pressure also flows through the pipe 140 into the cylinder 78 behind the piston 74. The pistons now move to the left to move the housing 46 toward the shell S and to force the knives 32 against the fuse ring F. During this movement of the pistons, the fluid in the left-hand end of the cylinders exhausts through the passageway 99, the passageway 102 in the valve member and the outlet port 94. The passageway 100 between the valve chamber and the cylinder 76 also communicates by way of a port 141 with the valve chamber behind the piston 98. After the pistons have moved sufficiently to force the knives 32 into contact with the fuse ring F, the pressure of the operating fluid will increase and will act on the valve piston 98 to overcome the holding effect of the latch 108, thereby moving the valve into the position shown in Fig. 7. With the valve member in this position, the passageway 99 is closed by the valve element 86 so that the fluid in front of the pistons 72 and 74 is trapped and the pistons stall, thereby limiting the force exerted by the knives on the fuse ring.

The piston 72 and rod 64 are provided with a passageway 144 (Fig. 5) which opens into the right-hand end of the cylinder 76 and the other end of the passageway is connected by a pipe 146 with a valve chamber 148 of a control valve 150. This valve chamber is formed in the housing 46, as shown in Fig. 4, and a passageway 152 provides communication with one of the cylinders 60 behind the piston 58 therein. Pipes 154 provide communication between the cylinder 60 of Fig. 4 and the other cylinders 60 so that upon the introduction of fluid under pressure into the cylinder shown in this figure, all the pistons 58 will be operated to move the pins 48 into locking engagement with the shell. The valve 150 comprises a valve member 156 which includes a pair of valve elements 158 and 160. The valve member is maintained in the position shown in Fig. 5 when the machine is at rest by a spring 162 acting through a bell-crank lever 164 on the valve stem 166. The spring 162 is adjustably supported by a screw 168 threaded in a wall 169 of the housing 46. When the valve member 156 is in the position shown in Fig. 5, the passageway 152 is closed by the valve member 158 to fluid under pressure in the pipe 146. The fluid under pressure behind the piston 72 acts through the passageway therein and the pipe 146 on the valve member 158 to move the valve member against the force of the spring 162 after the pressure reaches a value determined by the setting of the spring 162. The pressure reaches this value only after the valve member 84 has been moved from the position of Fig. 6 into the position of Fig. 7, whereupon the valve member 156 moves into the position of Fig. 9 permitting flow of fluid under pressure into the cylinders 60 to move the pistons 58 outwardly thereof whereupon the pins 48 are moved into engagement with the shell to lock it against rotation.

In order that the knives 32 will exert sufficient

gripping force on the fuse ring F for the purpose in view, it is preferable to force them by the movement of the pistons 72 and 74 into engagement with the fuse ring under considerable pressure, the shell being supported against rearward movement at this time by a stop 170 (Fig. 1) carried by the loading tray 16. It is desirable that the pressure on the fuse ring be decreased somewhat before it is turned to prevent binding of the fuse ring against the adjacent surface of the shell. For this purpose, fluid under pressure is admitted to the left-hand sides of the pistons 72 and 74. In the rod 66 of the piston 74 is provided a passageway 172, one end of which communicates with the cylinder 78 at the left of the piston (Fig. 5). The other end of this passageway communicates with one of the cylinders 60 (Fig. 5) through a pipe 174, a check valve 176 and a pipe 178. After the valve member 156 has been moved into the position of Fig. 9, causing the pins 48 to be moved into locking engagement with the shell, fluid under pressure flows through the pipe 178, check valve 176 and pipe 174 into the passageway 172 of the piston rod 66 and into the cylinder 78 to the left of the piston 74. The fluid also flows from the cylinder 78 through the pipe 142 into the cylinder 76 to the left of the piston 72. While it will be evident that the operating fluid acting on opposite sides of the pistons 72, 74 is under the same pressure per unit area, the effective areas of the pistons on their right-hand sides is greater than on their opposite, or left-hand sides, so that the effect of admitting pressure to the left-hand side of the pistons is to decrease the force exerted on the knives 32 to hold them in engagement with the fuse ring F with the result that the pressure of the knives on the fuse ring is reduced sufficiently to avoid any binding of the fuse ring such as might tend to prevent it from being turned freely relatively to other parts of the shell in the subsequent fuse-setting operation.

For turning the support 40 carrying the knives 32, thereby to set the fuse, a fluid-pressure motor 180 is provided. This is a rotary vane-type motor comprising a vane 182 keyed to a reduced portion 184 of the knives support 40 and rotatable within a cylindrical chamber 186 formed in the housing 46. The chamber 186 is provided with a wall 188 (Fig. 5) which extends radially inward to the hub of the vane 182. Ports 190 and 192 provide communication between the valve chamber 148 and the motor chamber 186 at opposite sides of the wall 188. A stop 194 in the chamber 186 prevents movement of the vane 182 to a position in which it would act to close the port 190. With the valve member 156 in the position shown in Fig. 9, fluid under pressure flows from the valve chamber 148 through the port 190 into the motor chamber 186 between the wall 188 and the vane 182, thereby causing movement of the vane in the direction of the arrow (Fig. 5). This rotative movement of the vane causes the support 40 carrying the knives 32 to turn, thereby turning the fuse ring F relatively to the shell S. The fluid within the motor chamber 186 exhausts through the port 192 and a port 196 in the valve chamber 148 which communicates with the fluid reservoir.

After the fuse ring has been turned through the desired angle to obtain the desired fuse setting, the pressure exerted on the vane 182 of the motor 180 is automatically cut off by movement of the valve member 156 from the position of Fig. 9 upwardly into the position shown in Fig. 10. In this

position, the valve element 158 closes the port 190 and the valve element 160 closes the port 192 so that the fluid within the motor is trapped and the motor comes to rest as soon as the valve member 156 is moved into the position of Fig. 10. For thus moving the valve into this position, the bell-crank lever 164 acting on the valve stem 166 is actuated at a predetermined time by the motor 180. Carried by the end of the reduced portion 184 of the support 40 is a bracket 200 in which is pivoted a bell-crank lever 202. One arm of this bell-crank lever has a forked end 204 received between collars 206 and 208 (Fig. 4) carried by a rod 210 extending axially through the support 40. This rod carries the plunger 44 by which the knives 32 are held in engagement with the fuse ring against the force exerted by the spring 42. The other arm of the bell-crank lever 202 carries a cam roll 210 which rides in contact with an adjustable cam 212 during the rotation of the support 40. The bell-crank lever 164 which is in engagement with the lower end of the valve stem 166 is connected by a link 214 to a crank arm 216 secured to a rockshaft 218 journaled in a housing 220 (Fig. 4) secured by screws 222 to the housing 46. Carried by the rockshaft 218 is an upwardly extending arm 224 having a forked end embracing the rod 210 to the right of the collar 208. When the machine is in the starting position, as shown in Figs. 4 and 5, the upper end of the arm 224 is spaced from the collar 208 sufficiently so that it will just move into engagement with the collar when the valve member 156 is moved into the position of Fig. 9. As the support 40 is turned by the motor 180, the cam roll 210 moves around the surface of the cam 212 and eventually rides up on a high surface 226 of the cam, thus pivoting the bell-crank lever 202 in a counterclockwise direction, as illustrated in Figs. 4 and 5. This movement of the bell-crank lever moves the rod 210 to the right, the collar 208 acting on the arm 224 secured to the shaft 218 to rock the shaft in a clockwise direction. This motion of the shaft acts through the arm 216, link 214 and bell-crank lever 164 to move the valve 156 upwardly against the force of the fluid under pressure acting downwardly thereon so that the valve moves into the position shown in Fig. 10 which immediately interrupts the operation of the motor 180, whereupon the support 40 stops turning. The movement of the rod 210 carrying the plunger 44 to the right causes the plunger to be moved out of operative engagement with the levers 34 on which the fuse-setting knives are carried so that the spring 42 is effective to move the knives out of engagement with the fuse ring simultaneously with the stopping of the motor 180.

For varying the fuse-setting time, the cam 212 is arranged to be adjusted to vary the angular motion required by the vane 182 to move the cam roll 210 to the high point 226 of the cam. The cam is provided with a hub 230 journaled in the housing 220 (Fig. 4) and extending into a gear housing 232 which is secured by a bracket 234 to the housing 220. Keyed to the hub 230 of the cam 212 is a pinion 236 which meshes with a pinion 238 secured to a shaft 240 journaled in the upper part of the housing 232, and this shaft is suitably connected with a remote control device 242 by which the shaft 240 may be turned a predetermined amount of rotation of a control handle 244 of the control member 242.

With the valve member 156 in the position shown in Fig. 10, the fuse is properly set and the knives 32 have been withdrawn from the fuse ring

so that the housing 46 may now be moved away from the shell back into its initial position. The pressure of the fluid behind the pistons 72 and 74 now increases, inasmuch as the flow through the passageway 144 in the rod 64 and the pipe 146 is cut off by the valve member 156 which is locked for the time being in the position shown in Fig. 10. Accordingly, the pressure which also acts on the piston 98 of the valve member 84 increases sufficiently to move the valve member once more to the left against the holding force of the latch 108. The valve is thus moved toward the left until the finger 106 carried by the valve stem 104 is moved beyond the lowest portion of the latch, whereupon the latch urged downwardly by the spring 112 acts through the surface 250 to move the valve still farther to the left until the finger 106 engages the rod 120, as shown in Fig. 8. Fluid under pressure now flows from the pipe 92 through the valve chamber and passageway 99 into the cylinder 76 to the left of the piston 72 and through the pipe 142 into the cylinder 78 on the same side of the piston 74. The fluid on the right-hand side of the pistons exhausts through the passageway 100 between the valve element 88 and the piston 98 past the check valve 96 back to the fluid reservoir. The valve 96 does not open to permit exhaust of fluid until the pressure on the right-hand side of the pistons has increased to a predetermined amount. This pressure is effective through the passageway 144 of the piston 72 and pipe 146 on the valve member 156 but is not sufficient to prevent movement of the valve by the spring 162 back to the position of Fig. 5. The fluid under pressure, however, flows through a passageway 252 which passes downwardly through the valve member 156 and opens into the space below the valve element 160. This passageway provides communication with the port 192 thereby to move the vane 182 back to its initial position, the fluid on the other side of the vane exhausting through port 190 and the port 196 back to the fluid reservoir.

The pistons 72 and 74 are now moved to the right, thus moving the housing 46 back to its initial position. During the return movement of the housing the screw 136 on the arm 138 of the housing acts on the finger 106 of the valve 84 to move the valve to the right until it reaches the position shown in Fig. 5 which is the rest position of the machine. As soon as this position is reached, the valve elements 86 and 88 close off the passageways 99 and 100, whereupon the machine immediately comes to rest. During this return movement, the knives 32 are reset, by movement of the plunger 44, into the position of Fig. 4. For thus moving the plunger, the rod 210 on which the plunger is carried extends beyond the gear housing 232 and engages the frame member 80 during the return movement of the housing 46. This causes movement of the rod 210 to the left, whereupon the member 44 moves into position between the adjacent ends of the levers 34 to move the knives 32 again into operative positions.

In the event that the pressure acting on the vane 182 of the motor 180 during the return movements of the parts is insufficient to move the vane 182 back to its starting position, this movement will take place immediately at the beginning of the next fuse-setting operation. The fluid under pressure will act through the passageway 144 of the piston rod 64, the pipe 146, passageway 252 of the valve member 156 and the port 192 to exert sufficient pressure against the

vane to return it and hold it in its starting position until the valve member 156 is moved to the position of Fig. 9. Normally, however, the back pressure set up by the check valve 96 in the discharge line will be sufficient to cause this return movement of the vane 182.

With the machine at rest, the parts will be in the positions shown in Fig. 5. Upon movement of a shell from the magazine 14 (Fig. 1) into fuse-setting position by the tray 16, the nose of the shell strikes the lower end 134 of the lever 130 (Fig. 4) which acts through the link 128 and the lever 126 to move the rod 120 (Fig. 5) to the right, which in turn causes movement of the valve member 84 into the position of Fig. 6. Fluid under pressure now flows into the cylinders 76 and 78 back of the pistons 72 and 74 to move the pistons to the left, which moves the housing 46 carried by the piston rods toward the shell. The knives 32 carried by the support 40 rotatable in the housing will thus be moved into engagement with the fuse ring F. After the knives have properly engaged the fuse ring, pressure to the right of the pistons 72 and 74 increases and acts on the valve piston 98 to move the valve member 84 into the position of Fig. 7 which traps the fluid to the left of the pistons 72 and 74 thus arresting movement of the housing 46. The fluid pressure now acts on the valve member 156 to move it into the position of Fig. 9 in which the fluid under pressure is effective to move the locking pins 48 into engagement with the shell back of the fuse ring to prevent rotative movement of the shell as the fuse is set. The fluid under pressure also acts on the pistons 72 and 74 to relieve the pressure of the knives on the fuse ring thereby eliminating possibility of binding of the fuse ring as it is turned. At the same time, the fluid under pressure acts on the vane 182 of the motor 180, starting rotation of the motor and turning of the fuse ring F. When the fuse ring has turned a predetermined amount, as determined by the setting of the cam 212, the valve member 156 is moved upwardly to the position of Fig. 10, thus trapping the fluid on both sides of the vane 182 and immediately stopping its rotation. At the same time the plunger 44 is moved to the left, thus permitting the knives 32 to be moved by the spring 42 out of engagement with the fuse ring. The valve member 84 is again moved to the left by the increase in pressure on the piston 98 until it assumes the position shown in Fig. 8, whereupon fluid under pressure flows into the cylinders 76 and 78 to the left of the pistons 72 and 74 to move them and the housing 46 back to their initial positions. The vane 182 of the motor 180 is also returned at this time and after the housing has moved sufficiently to the right, the knives 32 are reset by engagement of the rod 210 with the frame member 80, and the screw 136 carried on with the housing returns the valve member 84 to the position of Fig. 5, whereupon the machine comes to rest. The transfer tray 16 may now be operated to move the shell into alignment with the breech of the gun, whereupon the shell is rammed and the gun is fired by suitable mechanism (not shown).

Having thus described my invention, what I claim as new and desire to secure by Letters Patent of the United States is:

1. In a fluid-pressure-operated mechanism, a work-engaging member, a piston operatively connected thereto, a cylinder housing said piston, a passageway for directing fluid under pressure into said cylinder at one side of said piston for

moving the work-engaging member into engagement with a work piece under heavy pressure, a passageway for exhausting the fluid from said cylinder at the opposite side of said piston, valve means responsive to the pressure of the fluid in the cylinder at said one side of said piston for admitting fluid under pressure to said cylinder at said opposite side of said piston, and a valve operated in response to the pressure of the fluid in the cylinder at said one side of said piston to close the exhaust from said cylinder prior to the admission of fluid under pressure at said opposite side of said piston and subsequently to cut off the flow of fluid under pressure to said one side of said piston and to admit it into the cylinder at said other side of said piston thereby to move said piston and said work-engaging member in a reverse direction.

2. In a fluid-pressure-operated mechanism, a work-engaging member, a piston connected thereto, a cylinder housing said piston, a passageway for directing fluid under pressure to one end of said cylinder causing movement of said piston to force the work-engaging member into engagement with a work piece under heavy pressure, and means responsive to one predetermined pressure of the fluid in said one end of said cylinder arranged to provide communication between opposite ends of the cylinder after the work-engaging member has been moved under heavy pressure into engagement with the work piece and responsive to a higher predetermined pressure of the fluid in said one end of said cylinder to admit fluid to the other end of the cylinder and exhaust the fluid from said one end of the cylinder.

3. In a fluid-pressure-operated mechanism, a piston, a cylinder housing said piston, a passageway into one end of said cylinder for directing fluid under pressure thereto, an exhaust passageway at the other end of the cylinder for permitting the exhaust of the fluid from said end of the cylinder, valve means in said exhaust passageway operative in response to the pressure in said one end of said cylinder to close the exhaust passageway when the pressure reaches a predetermined value, means providing communication between opposite ends of the cylinder, and valve means in control of said last-named means responsive to the pressure in said one end of said cylinder arranged to permit flow of fluid therethrough after the valve in the exhaust passageway is closed.

4. In a fluid-pressure-operated mechanism, a piston, a cylinder housing said piston, said piston including a rod passing through an end of the cylinder, means admitting fluid under pressure into the other end of the cylinder, said rod having a passageway extending through the piston and terminating outwardly of the cylinder, means providing communication between said passageway and the other end of the cylinder, an exhaust passageway communicating with said other end of the cylinder, valve means responsive to the pressure in said other end of said cylinder in control of the means providing communication between the passageway and said other end of the cylinder, and valve means responsive to the pressure in said other end of said cylinder controlling said exhaust whereby the exhaust is closed prior to the flow of fluid from one end of the cylinder into the other.

5. In a fluid-pressure-operated mechanism, a work-engaging member, a pair of pistons operatively connected to said member for moving it

into and out of engagement with a work piece, a pair of cylinders housing said pistons, means admitting fluid into one end of each of said cylinders for moving said pistons conjointly to cause said work-engaging member to be moved into engagement with a work piece under heavy pressure, a pipe providing communication between the other ends of the cylinders, said pistons including piston rods extending through said other ends of each of said cylinders and being connected to the work-engaging member, a passageway extending through one of said pistons and the associated rod and terminating outwardly of the cylinder, the rod of said other piston having a passageway communicating with the passageway in the first piston and opening into the cylinder on the side of the piston from which the rod extends, and valve means responsive to the pressure in said one end of each of said cylinders in control of the flow of fluid from said first piston rod to the second piston rod.

6. In a fluid-pressure-operated mechanism, a work-engaging member, a pair of pistons operatively connected to said member for moving it into and out of engagement with a work piece, a pair of cylinders housing said pistons, means admitting fluid into one end of each of said cylinders for moving said pistons conjointly to cause said work-engaging member to be moved into engagement with a work piece under heavy pressure, a pipe providing communication between the other ends of the cylinders, said pistons including piston rods extending through said other ends of each of said cylinders and being connected to the work-engaging member, a passageway extending through one of said pistons and the associated rod and terminating outwardly of the cylinder, the rod of said other piston having a passageway communicating with the passageway in the first piston and opening into the cylinder on the side of the piston from which the rod extends, valve means operative in response to the pressure of the fluid in said one end of each of said cylinders in control of the flow of fluid from said first piston rod to the second piston rod, an exhaust from said cylinders on the sides of the pistons from which the rods extend, and a valve operative in response to the pressure of the fluid in said one end of each of said cylinders in control of said exhaust to close it before said first-named pressure-operated valve is opened to provide communication between the opposite ends of the cylinders.

7. In a fluid-pressure-operated mechanism, a work-engaging member, a pair of pistons operatively connected to said member for moving it into and out of engagement with a work piece, a pair of cylinders housing said pistons, means admitting fluid into one end of each of said cylinders for moving said pistons conjointly to cause said work-engaging member to be moved into engagement with a work piece under heavy pressure, a pipe providing communication between the other ends of the cylinders, said pistons including piston rods extending through said other ends of each of said cylinders and being connected to the work-engaging member, a passageway extending through one of said pistons and rod and terminating outwardly of the cylinder, the rod of said other piston having a passageway communicating with the passageway in the first piston and opening into the cylinder on the side of the piston from which the rod extends, valve means operative in response

to the pressure of the fluid in said one end of each of said cylinders in control of the flow of fluid from said first piston rod to the second piston rod, an exhaust from said cylinders on the sides of the pistons from which the rods extend, a valve operative in response to the pressure of the fluid in said one end of each of said cylinders in control of said exhaust to close it before said first-named pressure-operated valve is opened to provide communication between the opposite ends of the cylinders, and means for thereafter interrupting the flow of fluid under pressure into said one end of the cylinders and for causing it to flow directly into the other end of the cylinders to cause reverse movement of said pistons.

8. In a fluid-pressure-operated mechanism, a fluid-pressure motor, passageways for directing fluid under pressure to one side of the movable element of said motor and for exhausting fluid from the other side of the movable element, and means operative in response to progressive increases in the pressure of the fluid on said one side of the movable element for first cutting off the exhaust of fluid from said other side while the fluid is admitted to said first side, then admitting fluid under pressure to the other side while the fluid is admitted to the first side, and finally exhausting the fluid from the first side.

9. In a fluid-pressure-operated mechanism, a fluid-pressure motor, passageways for directing fluid under pressure to one side of the movable element of said motor and for exhausting fluid from the other side of the movable element, means operative in response to progressive increases in the pressure of the fluid on said one side of the movable element for first cutting off the exhaust of fluid from said other side while the fluid is admitted to said first side, then admitting fluid under pressure to the other side while the fluid is admitted to the first side, and finally exhausting the fluid from the first side, said means including a slide valve movable progressively into various positions in response to increases in pressure of the operating fluid, and means restraining said valve against such movement.

10. In a fluid-pressure-operated mechanism, a piston, a cylinder housing said piston, a valve chamber associated with said cylinder, passageways between said valve chamber and the cylinder communicating with opposite ends of the cylinder, intake and exhaust passageways in said valve chamber and a pressure-operated valve in said chamber movable progressively in response to progressive increases in pressure in one end of said cylinder from a position in which fluid under pressure passes through a passageway into said one end of the cylinder and exhausts through the passageway communicating with the other end of the cylinder, to a position in which said last-named passageway is closed to exhaust while the first-named passageway is open to the fluid under pressure, and to another position in which fluid under pressure exhausts from the first passageway communicating with said one end of the cylinder and enters the cylinder through said other passageway, said valve including an element exposed to the pressure of fluid passing through the passageway into said one end of the cylinder, and means restraining the valve against motion in response to such pressure.

11. In a fluid-pressure-operated mechanism, a piston, a cylinder housing said piston, a valve chamber associated with said cylinder, passage-

ways between said valve chamber and the cylinder communicating with opposite ends of the cylinder, intake and exhaust passageways in said valve chamber and a pressure-operated valve in said chamber movable progressively in response to progressive increases in pressure in one end of said cylinder from a position in which fluid under pressure passages through a passageway into said one end of the cylinder and exhausts through the passageway communicating with the other end of the cylinder, to a position in which said last-named passageway is closed to exhaust while the first-named passageway is open to the fluid under pressure, and to another position in which fluid under pressure exhausts from the first passageway communicating with said one end of the cylinder and enters the cylinder through said other passageway, said valve including an element exposed to the pressure of fluid passing through the passageway into said one end of the cylinder, and means restraining

the valve against motion in response to such pressure, said means including mechanism permitting step-by-step movement of the valve into said positions in response to a progressive increase in pressure against said element.

FRED C. EASTMAN.
